UNITED STATES PATENT OFFICE.

ETHELBERT S. GRIFFITH, OF NEW YORK, N. Y.

FOLDING COT-BED.

SPECIFICATION forming part of Letters Patent No. 242,197, dated May 31, 1881.

Application filed October 31, 1879.

To all whom it may concern:

Be it known that I, ETHELBERT SHEPHERD GRIFFITH, of the city of New York, county of New York, and State of New York, have invented a new and useful Improvement in Beds, of which the following is a specification.

My present invention, which relates to folding cots, has for its object to facilitate the folding up of the cot in a compact form; and it consists in the combination, in a folding bed, with the supports, pivoted together in pairs and arranged transversely to the side rails, and pivoted at their upper ends to the side rails, of braces the terminal ends of which are permanently connected with the side rails and the supports, all substantially as described, whereby the supports are maintained in proper position when the bed is in use, and adapted to fold into a parallel position with respect to the side rails when the rails are brought together, and to unfold when the rails are drawn apart, as hereinafter described.

In the drawings, Figure 1 represents a perspective view of my improved cot, showing the position the parts assume when unfolded and ready for use. Fig. 2 represents a perspective view, showing the cot folded. Fig. 3 represents a detached view, showing the method of attaching the legs to the side rails; and Fig. 4, a view showing a modified form of such connection.

The letter A indicates the side rails of the bed or cot, which, in connection with a suitable canvas or tick, form a proper support for the occupant. The said rails are preferably constructed in two parts, hinged together at C, so that they can be folded upon each other to reduce the bed or cot to the smallest possible compass for storage or transportation when required.

The letter B indicates the legs or supports of the cot or bed. These cross each other in pairs about midway between their two ends, and at their points of intersection are secured together

by means of suitable rivets or bolts in such 45 manner that they can be readily opened or closed. The upper ends of such legs or supports respectively are pivoted to the side rails by the connections D. These connections are in the nature of hinges, which permit the legs 50 or supports, which are pivoted together in pairs, as set forth, to be folded together on their central pivots, so as to bring the side rails together, the said connections being pivoted to the inner sides of the side rails by means of the bolts 55 e, as shown in Fig. 3, in such manner that they can be folded up longitudinally between said side rails, (excepting the central pair of supports, which will be folded against the inner sides of the side rails,) so as to lock the parts 60 of the cot rigidly when folded without the use of other fastening devices.

The letter E indicates a series of braces permanently connected at their terminals with the supports and with side rails, so that the supports will be maintained in proper position when the bed is in use, and be adapted to fold 65 into a parallel position with respect to the side rails when the rails are brought together and to unfold when said rails are drawn apart. 70

What I claim is—

The combination, in a folding bed, with the supports, pivoted together in pairs, arranged transversely to the side rails, and pivoted at their upper ends to said rails, of braces the 75 terminal ends of which are permanently connected to the side rails and the supports, all substantially as described, whereby the supports are maintained in proper position when the bed is in use, and adapted to fold into a 80 parallel position with respect to the side rails when the rails are brought together, and to unfold when the rails are drawn apart, as set forth.

ETHELBERT SHEPHERD GRIFFITH.
